(57) CLAIM

The ornamental design for a napkin holder, as shown and described.

DESCRIPTION

FIG. 1 is a perspective view of a napkin holder, showing our new design;

FIG. 2 is a front view of the flat napkin holder of FIG. 1;
FIG. 3 is a rear view of the flat napkin holder of FIG. 1;
FIG. 4 is a side view of the flat napkin holder of FIG. 1;
FIG. 5 is a top view of the flat napkin holder of FIG. 1; and,
FIG. 6 is a bottom view of the flat napkin holder of FIG. 1. The broken line portions show unclaimed subject matter only and form no part of the claimed design.
